CLAIM

The ornamental design for an electronic driver's license case with biometric verification means, as shown and described.

(21) Appl. No.: **29/435,725**

DESCRIPTION

(22) Filed: **Oct. 26, 2012**

FIG. 1 is a top perspective view of the electronic driver's license case with biometric verification means.

(51) **LOC (9) Cl. 03-01**

FIG. 2 is a bottom perspective view of the electronic driver's license case with biometric verification means.

(52) **U.S. Cl.**

FIG. 3 is a top plan view of the electronic driver's license case with biometric verification means.

USPC **D3/249**

FIG. 4 is a bottom plan view of the electronic driver's license case with biometric verification means.

(58) **Field of Classification Search**

FIG. 5 is a right side view of the electronic driver's license case with biometric verification means.

USPC D3/247, 249-253; 206/235, 265

FIG. 6 is a left side view of the electronic driver's license case with biometric verification means.

See application file for complete search history.

FIG. 7 is a front view of the electronic driver's license case with biometric verification means; and,

(56) **References Cited**

FIG. 8 is a rear view of the electronic driver's license case with biometric verification means.
